FOLDING AND ADJUSTABLE STEREOSCOPE

Thomas N. Hubbard, P.O. Box 105,
Northbrook, Ill. 60042

Filed Mar. 7, 1966, Ser. No. 1,306

Term of patent 14 years

(Cl. D57—1)

fig.2.

fig.3.

FIGURE 1 is a top plan view of a folding and adjustable stereoscope, embodying my new design;

FIGURE 2 is a side elevation thereof, with portions of the leg support omitted for convenience of illustration;

FIGURE 3 is an end elevation thereof, with portions of the leg support omitted; and

FIGURE 4 is a transverse section taken on line 4—4 of FIGURE 1.

I claim:

The ornamental design for a folding and adjustable stereoscope, as shown and described.
